ORAL HYGIENE APPLIANCE AND COVER

Richard S. Hart, Batavia, Ill., assignor to Sunbeam Corporation, Chicago, Ill.

Filed June 21, 1972, Ser. No. 264,761

Term of patent 14 years

Int. Cl. D24—03

U.S. Cl. D24—1 B

FIG. 1 is a front perspective of an oral hygiene appliance, showing my new design;

FIG. 2 is a front elevation with the transparent cover removed for clarity of illustration;

FIG. 3 is a top plan view thereof;

FIG. 4 is a side elevation thereof;

FIG. 5 is a rear elevation thereof; and

FIG. 6 is a cross-section taken on line 6—6 of FIG. 2.

The broken lines are shown for illustrative purposes only.

I claim:

The ornamental design for an oral hygiene appliance and cover, as shown and described.
